UNITED STATES PATENT OFFICE.

CHRISTIAN E. LIEBENBERG, OF ESSINGTON, PENNSYLVANIA.

TROLLEY-WHEEL.

1,391,741.

Specification of Letters Patent. Patented Sept. 27, 1921.

Application filed July 22, 1920. Serial No. 398,113.

To all whom it may concern:

Be it known that I, CHRISTIAN E. LIEBENBERG, a citizen of the United States, residing at Essington, county of Delaware, and State of Pennsylvania, have invented certain new and useful Improvements in Trolley-Wheels, of which the following is a specification.

My invention relates to trolleys or other contact members such as are used in connection with electric street cars, and has for its object to provide a strong and simple construction of the type in which the contact member proper is combined with a guard which is normally inactive, but when the said member comes off the power wire, becomes operative to keep the contact member in the neighborhood of the wire and facilitate its restoration to normal position.

A satisfactory and preferred embodiment of my invention will now be described in detail with reference to the accompanying drawings, and the novel features will then be pointed out in the appended claims.

In said drawings Figure 1 is a side elevation of my improved contact member in conjunction with a power wire; Fig. 2 is an inverted plan view thereof, the wire being omitted; Fig. 3 is a detail view of certain parts, viewed in the direction of the arrow 3 in Fig. 1, but showing the springs in a different position; and Fig. 4 is a partial cross section, substantially on the plane indicated by the line 4-4 of Fig. 2.

10 designates the trolley pole and 11 the harp at the upper end of said pole, it being understood that these parts are pressed upwardly by the usual spring (not shown). The upper end of the harp is made with a double fork, that is to say, it has a left-hand fork member and a right hand fork member spaced therefrom as shown in Fig. 2, and each of these fork members comprises an upper arm 11' and a lower arm 11'', with an opening 11^a between them. With the upper end of each arm 11' and of the companion arm 11'' is connected a boss or bearing 12, extending outwardly from the left-hand and right-hand fork member respectively, and provided with axially-aligning openings in which are journaled trunnions 13. By means of cotter pins 14 or other suitable devices, these trunnions are connected with the side members of a trolley wheel carrier and guard. As shown this part of the structure is made of two similar sheet-metal members 15 and 16, bent into channel-shape so as to

have parallel flanges 15', 16' respectively, and having their ends bent as at 15'', 16'' for a screw-and-nut connection 17. The members 15, 16 have transversely-aligning holes to receive an axle 18, held against turning and against longitudinal movement by a cotter pin 14' extending through the flanges of one of said members. Adjacent to this point, the members 15 and 16 are substantially parallel (see Fig. 2) and between these parallel portions extends the trolley wheel 19, mounted to turn on the axle 18, and adapted to engage the power wire A. Between the axle 18 and the connection 17, the guard and carrier members 15, 16 are much farther apart, so as to come outside the bosses or bearings 12. At their free ends, the members 15, 16 diverge or flare outwardly from their parallel portions, as indicated at 15^a, 16^a.

The entire carrier 15, 16 with the wheel 19 is thus mounted to turn relatively to the harp 11 about the axis of the bearings 12, the axis of the trolley wheel 19 being eccentric to said pivot axis of the carrier 15, 16. On a transverse pin 20 located near the base of the harp 11 are coiled two springs 21 located between the side members of the harp, the adjacent or inner ends of the springs engaging the carrier 15, 16, while the other ends of the springs engage the harp (although of course the arrangement might be reversed) with a tendency to cause the free ends of the carrier to swing upward relatively to the harp. The power of the main spring (not shown) actuating the trolley pole is sufficient to overcome that of the springs 21 under normal conditions, so as to keep the parts in the position indicated by full lines in Fig. 1, the carrier 15, 16 in that position being below the level of the wire A and of the uppermost portion of the wheel 19.

Should the wheel 19 come off the wire A, the springs 21 will swing the carrier 15, 16 upward on the pivot 13 to the position indicated by dotted lines in Fig. 1, (see also the position of the springs 21 in Fig. 3) the upper flanges 15', 16' coming into engagement with stop shoulders 11^b formed on one or both of the side members of the harp. In this position, a portion of the members 15, 16, and particularly the diverging free ends thereof, 15^a, 16^a, extend not only to and above the level of the power wire A, but even above the uppermost portion of the wheel 19, although the latter itself is raised sufficiently to bring its center about level with the power

wire. By this arrangement, the wheel 19 will be kept in the neighborhood of the wire A, and it will be easy to restore the parts to the proper operative position.

5 At 22' I have indicated means for securing to the harp, a contact plate 22 adapted to engage the wheel 19 on one side, said plate passing through one of the openings 11^a. Any other suitable means may be employed 10 for making a good electrical connection with the trolley wheel 19.

The distance between the pin 20 and the bearing points of the springs on the united end members of the carrier increasing as the 15 latter swings upwardly, causes a rapid variation of the pressure of the springs on the carrier. By this means the shock or impact as the carrier is stopped at either end of its movement is reduced to a minimum as the 20 springs can be made of nearly sufficient strength to counterbalance the main spring actuating the trolley pole when in normal position, while, as the pressure of the springs rapidly decreases as the guard swings upwardly the latter is not swung violently 25 against the shoulders 11^b of the harp. Furthermore the relatively high pressure of the springs on the guard at the initial upward movement thereof insures of a quick 30 response to offset any downward movement of the trolley pole.

While I have illustrated my invention in connection with a current-collector or contact member consisting of a trolley wheel, 35 I desire it to be understood that other forms of contact members (such as the well-known shoe) may be used instead.

I claim as my invention:

1. In a device of the class described, a 40 harp having a forked end, a carrier and guard pivoted on said harp, a trolley wheel carried by said carrier and guard, a spring arm attached to the harp and bearing in said carrier and guard and urging the same 45 upwardly, the point of engagement of said arm with said carrier and guard increasing

in distance from its point of attachment to the harp as the carrier and guard moves upwardly relatively to the harp.

2. In a device of the class described, a 50 harp having a forked end, a carrier and guard comprising a pair of side frame members having their main lengths substantially horizontal and having downturned forward ends united under the said harp whereby 55 movement of the carrier and guard in a downward direction is limited by engagement of said united ends with the harp, means whereby said carrier and guard is pivoted in the harp adjacent the downward 60 bend thereof, a pin fixed in and extending between the forked members of the harp, at a point between the pivotal axis of the carrier and guard and the said united end thereof, a spring coiled around said pin 65 and bearing at one end on said end of the carrier and guard and normally urging the latter upward.

3. In a device of the class described, a 70 harp having a forked end, a carrier and guard comprising a pair of side frame members pivoted in the forked end of the harp and having their main lengths substantially horizontal and having downturned forward ends united under the said harp whereby 75 movement of the carrier and guard in a downward direction is limited by engagement of said united ends with the harp, a trolley wheel carried by said carrier and guard, said horizontal members of the guard 80 being inturned toward one another adjacent the rear of the forked end elements of the harp, radially projecting shoulders formed on the said forked end elements of the harp and adapted to engage the said inturned 85 parts of the carrier and guard to limit upward movement thereof, and means normally urging said carrier and guard upward.

In testimony whereof I have affixed my 90 signature.

CHRISTIAN E. LIEBENBERG.
